(57) **CLAIM**

The ornamental design for a spring pin tip, as shown and described.

DESCRIPTION

FIG. 1 is a top front right side perspective view of a spring pin tip showing my new design;

FIG. 2 is a top rear left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The features shown in broken lines depict environmental subject matter only and form no part of the claimed design.

1 Claim, 4 Drawing Sheets(56)
